UNITED STATES PATENT OFFICE.

ALEXANDER WATTERS, OF CHICAGO, ILLINOIS.

LOOSE-LEAF BOOK.

No. 883,154.

Specification of Letters Patent. Patented March 24, 1901

Application filed December 19, 1906. Serial No. 348,543.

To all whom it may concern:

Be it known that I, ALEXANDER WATTERS, a resident of Chicago, in the county of Cook and State of Illinois, have invented certain new and useful Improvements in Loose-Leaf Books, of which the following is a full, clear, and exact description.

The invention relates to loose-leaf books or binders, such as are commonly employed for ledgers or other books.

The invention designs to provide an extensible book or binder which is simple in construction and can be manufactured at a low cost.

15 The invention consists in the novel features hereinafter set forth and more particularly defined by claim at the conclusion hereof.

In the drawings: Figure 1 is a perspective of a loose-leaf book embodying the invention. Fig. 2 is a face view of the extensible back and the adjustable connection between the sections thereof, parts being shown in section. Fig. 3 is a plan of the parts shown in Fig. 2, some parts being shown in 25 section. Fig. 4 is a central longitudinal section through the adjusting means. Fig. 5 is a perspective of the adjusting screw and the key for operating the same. Fig. 6 is a detail of the reinforcing strip which secures the 30 adjusting screw against longitudinal movement in one of the back-sections.

The book or binder comprises sides *a* and *b* each of which is hinged or flexibly connected as at 10, to one of the sections of the extensible back. Said back comprises a pair of angular strips *c* and *d* the vertical portions *c'* *d'* whereof are arranged to over-lap each other to form a closed extensible back. Usually a covering 11 of any suitable material is provided for each of the back-sections. The side-walls or flanges of these sections form adjustable clamping-members between which the leaves or sheets of the book may be secured. The angular strip *c* is reinforced by 45 a transverse strip 13 secured to the inner face of its side and the angular strip *d* is likewise reinforced by a strip 11. The horizontally extending flange or wall and member *d* have secured thereto a plurality of posts *e* which are riveted to said flange as at *e'* and which secure the strip 11 to said flange, and to the horizontal flange or wall of member *c* are secured as at *f'* a plurality of hollow posts or guides *f* in which the posts are adapted to fit 55 and slide. The riveted ends *f'* also secure

the strip 13 to said wall of member *c*. The inner ends of said posts are tapered to facilitate passage through perforations in sheets *g*. A central tubular post *h* is secured to the member *d* and said post is provided with an internal screw-thread *h'* adapted to engage a screw-threaded post *i* which is revolubly connected to the other member. The upper end of screw *i* extends through a perforation in the horizontal flange of member *c* and is 60 provided with an annular shoulder or flange *i'* which fits in a socket or recess 12 formed in strip 13 which is also secured to member *c* by rivets 14. Screw rod *i* is provided with a socket 15 adapted to receive a suitable 65 key or crank 16 whereby the screw may be turned. Member *c* is provided with a key opening 17 through which the key may be inserted into post *i*. The flanges *i'* of screw *i* is held in socket 15 and between strip 70 13 and the horizontal wall of member *c* to hold the screw against longitudinal movement and so that it may be turned with respect to member *c*. The inner end of tubular post *h* is tapered to facilitate passage of 75 the post through perforations in the sheets.

The construction of the angular members is such that they may be made of stout sheet-metal. The reinforcing strips provide a surface devoid of projections and a double 80 thickness of metal is provided at the points where the posts and tubes are secured to the clamping-members to form a firm attachment for the posts and tubes.

In use, the members can be disconnected 85 to permit the sheets to be adjusted by-rotating screw *i*. The posts and connections between the members serve to maintain the parallel relation of the members and to secure them against relative endwise shift. By adjusting the screw *i* the sheets can be securely clamped and held between members *c* and *d*, the overlapping back-portions of said members serving to effectively close and protect the back edges of the sheets.

100 The construction is a simple and durable one and entirely avoids the use of projecting parts.

Having thus described the invention, what I claim as new and desire to secure by Letters 105 Patent is:

In a loose-leaf book or binder, the combination with a pair of angular members having sides and overlapping back portions, and interfitting posts and tubes respectively se- 110

cured to said members, of a central tubular internally screw-threaded post secured to the side of one of the angular members, an adjusting screw within said tubular post having a flange at its outer end, and a strip fixed to the inner side of the other of said angular members and having an outer socket

therein in which the flange of said screw is revolubly held between said strip and said angular member.

ALEXANDER WATTERS.
